DESIGN FOR A COMBINED BOTTLE POURER AND CAP THEREFOR

Joseph Harris Reinfeld, Newark, N. J., assignor to
Wilson Distilling Co. Inc., Bristol, Pa., a cor-
poration of Maryland

Application May 23, 1939, Serial No. 85,171

Term of patent 7 years

To all whom it may concern:

Be it known that I, Joseph Harris Reinfeld, a citizen of the United States and resident of Newark, in the county of Essex and State of New Jersey, have invented a new, original, and ornamental Design for a Combined Bottle Pourer and Cap Therefor, of which the following is a specification, reference being had to the accompanying drawing, forming a part thereof and in which:

Figure 1 is an inverted perspective view of a combined pourer and cap therefor illustrating the elements separated showing my new design;

Figure 2 is a top perspective view thereof with the pourer and cap in assembled position;

Figure 3 is a view in side elevation of the pourer forming part of the unitary design shown in Figures 1 and 2;

Figure 4 is a top plan view of the pourer forming part of the unitary design shown in Figures 1 and 2, and

Figure 5 is a bottom plan view of the pourer forming part of the unitary design shown in Figures 1 and 2.

I claim:

The ornamental design for a combined bottle pourer and cap therefor, substantially as shown.

JOSEPH HARRIS REINFELD.
